(57) **CLAIM**

The ornamental design for an anal irrigation cone, as shown and described.

DESCRIPTION

FIG. 1 is an isometric view of a design for an anal irrigation cone;

FIG. 2 is a front side view thereof;

FIG. 3 is a back side view thereof;

FIG. 4 a right side view thereof;

FIG. 5 is a left side view thereof;

FIG. 6 is a top side view thereof; and,

FIG. 7 is a bottom side view thereof.

The broken lines of FIGS. 2-5 and FIG. 7 form no part of the claimed design.

1 Claim, 7 Drawing Sheets
